TUNABLE MAGNETRON

John S. Donal, Jr., Princeton, N. J., Lloyd P. Smith, Ithaca, N. Y., and Barremore B. Brown, Lancaster, Pa., assignors to Radio Corporation of America, a corporation of Delaware

Application July 2, 1947, Serial No. 758,692

17 Claims. (Cl. 315—40)

1

This invention relates to magnetrons, and particularly to constructional features thereof significant in selection of their operating frequencies.

In accordance with the invention, the anode of a magnetron tube is divided into portions or blocks which may be relatively adjusted to predetermine or vary the effective length of the anode in selection of the operating frequency. More specifically, in a tunable magnetron at least one of aforesaid blocks is mechanically coupled to a member which is movably mounted within the evacuated envelope of the magnetron and is adjustable in accordance with the change in setting of an external tuning member suitably coupled thereto.

Further in accordance with the invention, the resonant cavities of the magnetron may be defined by vanes extending from the anode blocks into overlapping relation with one another; preferably, the overlapping ends of each pair of vanes respectively extending from the opposed anode blocks are complementarily stepped to maintain a long flux-leakage path between adjacent cavities for all relative positions to which the blocks may be adjusted. More specifically and preferably, the adjacent vanes of each block have the steps on opposite faces thereof in avoidance of distortion of the current paths in the cavity walls formed in part by the vanes.

The invention further resides in features of construction, combination and arrangement hereinafter described and claimed.

For more detailed understanding of the invention and for illustration of embodiments thereof, reference is made to the accompanying drawings in which:

Figure 1 is a plan view, in section taken on line 1—1 of Figure 2, of a tunable magnetron;

Figure 2 is a front elevational view taken on line 2—2 of Figure 1;

Figure 3 is a sectional plan view taken on line 3—3 of Figure 2;

Figure 3A is a front elevational view of one of the anode blocks of Figures 1 to 3;

Figure 4 is a fragmentary perspective view of the anode blocks of Figures 1 to 3;

Figures 5 and 6 are sectional plan views of modifications of the tuning means shown in Figures 1 to 3;

Figure 7 is a sectional view taken on line 7—7 of Fig. 9 of a magnetron tunable by variation of the orientation of its envelope with respect to its anode structure and field magnet;

Figure 8 is a detail end view taken on line 8—8 of Figure 7;

Figures 9 and 10 are sectional end views taken on line 9—9 of Figure 7 for different angular positions of the magnetron envelope relative to its anode structure and magnet; and

2

Figure 11 is a perspective detail view of parts appearing in Figure 7.

Referring to Figures 1 to 4 as exemplary of one form of the invention, the anode 10 of magnetron 11 is formed by two relatively movable anode blocks 12, 13 disposed side by side within the evacuated envelope 9 and having aligned cylindrical openings. The anode block 12 is fastened to the rods or bolts 14 whereas the block 13 is 5 slidable along them to predetermine or vary the operating frequency of the magnetron as later herein more specifically described. The cavity resonators or slots 15 of the magnetron are separated by two sets of anode vanes 16A, 16B, 10 Figures 3 and 4. The vanes 16A extend radially into the cylindrical opening in block 12 and vanes 16B extend radially into the similar opening in block 13. The inner faces of the vanes 16A, 16B provide spaced parallel anode elements which 15 form a peripherally discontinuous anode cylinder concentric with respect to the cathode C supported by one or both of the inserts or pole pieces 17, 18. When, as in copending application, Serial No. 751,730, filed June 2, 1947, by John S. Donal, Carmen L. Cuccia, and Barremore B. Brown, and 20 entitled Magnetrons, and now abandoned, a dual cathode is employed, the secondary emission cathode is preferably mounted in the magnetic insert 18 and the primary emission cathode is 25 maintained in the magnetic insert 17. For reasons which later appear, this avoids flexing of the heater leads to the primary emission cathode. 30

As the separation between the anode blocks 12, 13 is increased, the effective length of the anode is increased and in consequence the operating frequency of the magnetron is decreased. It is desirable that the vanes 16A, 16B overlap to maintain continuity of the side walls of each of the anode cavities 15 with increasing separation 35 of the blocks 12, 13 as otherwise the divided halves of the cavity may resonate individually producing undesired frequencies in the spectrum of the cavity. Throughout the range of relative adjustment of blocks 12, 13 the vanes 16A of block 12 project into the anode cavities of block 13, and conversely, the vanes 16B of block 13 continuously project into the anode cavities of block 12.

Preferably, as shown in Figure 4, the overlapping ends of each pair of vanes 16A, 16B are complementarily stepped or notched not only to maintain the continuity of each cavity 15 which could be effected by overlapping without notching but also to insure that the flux-leakage path 45 between adjacent cavities is long so effectively to suppress undesired couplings between the different cavities for all relative positions to which the anode blocks may be adjusted.

It is also desirable, as shown in Figure 4, that 50 the steps or notches be on opposite faces of the

adjacent vanes of each block in avoidance of distortion of the path of the currents flowing in each half of each cavity. Otherwise expressed, the cut-away surface of each vane faces the cut-away face of the vane adjacent it in one direction and its uncut surface faces the uncut surface of the vane adjacent to it in the other direction. The current paths are therefore of similar configuration in the opposed radial surfaces of each anode cavity; this would not be so if, for example, all of vanes 16A were cut away on the right face and all of vanes 16B were complementarily cut away on the left face. The dissymmetry so introduced in each cavity, and here avoided, would undesirably affect the operating characteristics of the magnetron.

As thus far described, the constructional features provide for determination of the operating frequency of a magnetron by adjustment of its anode length whether the adjustment be effected during construction in predetermination of its operating frequency or whether the adjustment be effected after construction of the magnetron to vary its operating frequency without destroying the integrity of its evacuated envelope.

The remainder of the description is for the most part concerned with alternative arrangements for effecting relative adjustment of the anode blocks 12, 13 of a turnable magnetron. In the modification shown in Figures 1 to 4, a pair of externally threaded sleeves 19, which are rotatably mounted on the rods 14 engage threaded openings through the movable anode block 12. The crank arms 20, Figures 1 and 2, extending from the threaded sleeves 19 are mechanically coupled to the reciprocable operating member 21 which may be fastened to the closed end of a bellows or "Sylphon" 22 which forms a deformable section of the evacuated envelope 9 of the magnetron. By application of force externally applied to the closed end of bellows 22, the bar 21 may be moved to the left or right within the envelope 9, to effect rotation of the sleeves 19 and so effect linear movement of the anode block 13 toward or away from the anode block 12. Axial movement of the sleeves 19 is minimized or eliminated by the thrust washers or collars 23, 24.

For adjustment of the bar 21 to different positions corresponding with different operating frequencies, there is attached to the external face of bellows 22 a post 25 which threadably engages the tuning member or screw 26 provided with a knob 27 for convenience in manual tuning. The shaft or screw 26 is journaled in the outer end of a hollow post or column 28 extending from the tube envelope 9 and forming a protective housing for bellows 22. Axial movement of the tuning shaft 26 is precluded by the thrust collars 29, 30 or equivalent.

The tuning range afforded by adjustment of the separation between the anode blocks of the magnetron is substantial. For example, a particular magnetron may be tuned to a selected frequency within the range of from about 9900 megacycles to about 10,100 megacycles, by providing for a total variation of spacing of the order of 0.050" which can be effected by movement well within the limits of a bellows 22 suited to withstand atmospheric pressure.

The rods 14 not only provide support for the movable anode block 13 and its operating sleeves 19, but may also mechanically connect both anode blocks, the pole pieces 17, 18 and the cathode, to form an assembly fastened as a unit to the blocks

31 which are suitably secured to the stationary anode block 12 and to the base 11 of envelope 9. More specifically, each of the rods 14, Figure 3, passes at one end through an insulating washer 5 32, an insulating sleeve 33 and a cross-piece 34 and at its other end through the insulating collars or washers 35, 36 and the cross-piece 37. The two cross-pieces 34, 37 respectively carry the pole pieces or magnetic inserts 17, 18 which, 10 as above stated, may support the cathode or cathodes of the tube within the anode blocks 12 and 13. In the drawing, a cathode C, of conventional tubular form, is shown as supported by the insert 18. The cathode is broken away in 15 some of the figures to show the anode vane structure. Thus, when the bolts 14 are tightened, all components of the electrode assembly are held fast except for the relative movement of the anode blocks previously described.

20 In the modification shown in Figure 5, a generally similar electrode assembly may be used and consequently only the differences in construction are specifically mentioned. In this modification, instead of the threaded sleeves 19, there are 25 cams or eccentrics 38 which bear against the outer face of the movable anode block 13A which is biased away from the stationary block 12A as by springs 39 received by recesses 40 in the opposed faces of blocks 12A, 13A. The operating bar 21A is coupled to the cams 38 as by pin and slot connections 41, 42 and may be connected to a bellows, as in Figure 1, for tuning adjustment externally of the tube envelope.

25 In the modification shown in Figure 6, the angular movement of threaded sleeves 19A, similar to the sleeves 19 of Figs. 1-3, for adjustment of the movable anode block 13 is effected by a worm gear arrangement including worm wheels 43 attached to the sleeves 19A and worms 44 attached to the operating shaft 21B which is suitably supported by bearing members 45 attached to the tube envelope 9. For effecting change in effective length of the anode 10 by a force applied externally of the tube envelope, there may be utilized a pair of magnetic members 46, 47, one or both of which may be powerful permanent magnets, magnetically coupled to each other through the extension 28A of the evacuated tube housing 9. The member 46 attached to shaft 21B within extension 28A may, for example, serve as the armature of magnet 47 externally rotatably mounted on the envelope extension 28A. By rotation of the external tuning member 47, the effective length of the magnetron anode may be increased or decreased to obtain the desired operating frequency as checked, for example, by a calibrated wave-meter of suitable type.

30 In still another form of the invention shown in Figures 7 to 11, the anode length and therefore the operating frequency may be adjusted 35 simply by varying the position of the magnetron with respect to its field magnet.

35 At opposite ends of the cylindrical envelope 58 of the magnetron, there are attached two fixed cams 51, 52 similarly oriented with respect to the axis of the envelope. The anode blocks 12B and 13B, generally similar to those previously herein-described, are provided with slots 53 which receive the cams 51 and 52, the engagement between the sides of the cams and the side walls of the anode blocks preventing movement of the blocks axially of the envelope. The blocks 12B and 13B are biased toward each other and into engagement with the faces of the cams 51, 52, by two pairs of springs 54 or equivalent.

The blocks 12B and 13B are slidably mounted on a pair of H-shaped frames or supports, each comprising a cross-piece 56 free to rotate about the axis of cams 51, 52 and a pair of end pieces 57 extending parallel to the axis M—M of the cylindrical anode space. As shown, the cross-pieces 51 may be slotted to receive pins 58 extending from the blocks 12B, 13B. The elongated slots permit the blocks to move bodily toward or from each other but prevent movement of either of them in direction normal to the axis M—M.

The anode blocks and their supports may be rotated as a unit with respect to the tube envelope 50 about the axis of fixed cams 51, 52 and the anode blocks may move linearly in direction along the axis M—M of the anode space.

Accordingly as the envelope 50 of the magnetron is rotated about its longitudinal axis, the cams 51, 52 and springs 54 are effective to change the spacing between the anode blocks 12B, 13B and therefore effective to change the operating frequency of the magnetron by variation of its anode length. The magnetic attraction between the pole pieces 17, 18 and the powerful field magnet 59 prevents rotation of the anode blocks as the envelope is rotated to different angular positions relative to the field magnet. Therefore, since the cams 51, 52 are attached to and rotate with the envelope, they are effective during rotation of the envelope to separate the anode blocks or to allow them to move toward one another under influence of the biasing springs 54. In Figure 9, the relative positions of the parts are shown for maximum anode length or lowest frequency; the points of engagement between the anode blocks and the cams are at the maximum cam diameter. Upon rotation of the magnet or the tube about the axis of the tube envelope 50 through an angle of 90° to the position shown in Figure 10, the internal parts assume the positions there shown with the cams at their minimum diameter engaging the anode blocks, to afford minimum anode length or highest operating frequency.

To minimize any change in the coefficient of coupling between the magnetron and its load circuit as the magnetron is rotated, it is provided that the position of the coupling loop 61 with respect to the anode cavity of the magnetron shall not change as the tube envelope is rotated. More specifically, the concentric output line 60 whose inner conductor 62 is formed into the coupling loop 61 lies in the axis of rotation of the envelope. The sleeve 63 which forms an extension of the outer conductor of line 60 is free to rotate on that portion of the outer conductor which is fastened to the envelope to serve as a mount for the fixed cam 52. The open end of the sleeve 63 is connected to the looped end 61 of the inner conductor 62 which is free to rotate inside of the line 60. The disk 64 or equivalent is attached to the sleeve 63 and projects into slots 65 of the anode blocks to prevent movement of the sleeve 63 and loop 61 axially of the envelope: rotation of the sleeve and loop with respect to the blocks is prevented by a pin and slot or equivalent connection between at least one of the blocks 12B, 13B and the disk 64 or other element fastened to sleeve 63. Accordingly, as the tube envelope 50 is rotated, the anode assembly and coupling loop remain fixed with respect to the field magnet 59 except for relative rectilinear tuning movement of the anode blocks 12B,

13B which is under control of cams 51, 52 and springs 54.

The external portion of the output line 60 may project into a wave guide or a resonant cavity, that portion of its inner conductor 62 which extends beyond the outer conductor, to the left in Figure 7, serving as a probe or antenna whose position remains effectively fixed notwithstanding rotation of the magnetron for tuning of its operating frequency.

It shall be understood the invention is not limited to the specific arrangements disclosed and that changes and modifications may be made within the scope of the appended claims.

What is claimed is:

1. A tunable magnetron comprising an evacuated envelope, an anode comprising spaced relatively movable anode blocks within said envelope, a cathode positioned within said anode blocks, and means within said envelope connecting said blocks independently of said envelope, said means being adjustable for varying the effective length of said anode by adjustment of the separation between said anode blocks.

2. A tunable magnetron comprising an evacuated envelope, an anode comprising spaced relatively movable anode blocks disposed side by side within said envelope, a cathode positioned within said anode blocks, means within said envelope connecting said blocks independently of said envelope, said means being adjustable for varying the separation of said blocks to adjust the effective length of said anode and including a tuning member and means externally of said envelope and coupled to said member for operating the latter.

3. A tunable magnetron comprising an evacuated envelope having a deformable section, an anode comprising relatively movable anode blocks disposed within said envelope, a cathode positioned within said anode blocks, adjustable mechanical means within said envelope connecting said blocks independently of said envelope, and means for transmitting motion through said deformable section to said mechanical means to vary the effective length of the anode by adjustment of the separation of said anode blocks.

4. A tunable magnetron comprising an evacuated envelope, an anode comprising relatively movable blocks within said envelope, and means for varying the effective length of said anode comprising magnetic members respectively attached to said blocks, and cam structure attached to said envelope and engaging said blocks, the orientation of said envelope with respect to an external magnet which restrains said magnet members from rotation with the envelope determining the spacing of said anode blocks.

5. A tunable magnetron comprising an evacuated envelope, an anode comprising relatively movable blocks within said envelope, and magnetic means for varying the effective length of said anode comprising a magnetic member movably mounted within said envelope and mechanically coupled to one of said blocks, and means movably mounted adjacent the exterior of said envelope for producing a magnetic field operable on said magnetic member within said envelope, whereby movement of said field producing means with respect to said envelope will cause movement of said magnetic member and said one of said blocks and thus vary the spacing of said blocks.

6. A tunable magnetron anode comprising a pair of anode blocks mounted parallel to each

other for relative movement, said magnetron anode having a plurality of cavity resonators separated by pairs of vanes respectively extending from the blocks with the vanes of each pair in overlapping relation, and means connecting said blocks, said means being adjustable for uniformly varying the spacing between said blocks to adjust the effective length of the anode and without disturbance of the symmetry of said resonators.

7. A magnetron anode comprising spaced blocks disposed side by side and whose effective length is determined by the separation between said blocks, said magnetron anode having a plurality of cavity resonators separated by pairs of vanes respectively extending from the blocks with the vanes of each pair in overlapping relation.

8. A magnetron anode comprising spaced blocks disposed side by side and having aligned openings and whose effective length is determined by the distance between said blocks, said magnetron anode having a plurality of cavity resonators separated by pairs of vanes respectively extending from the blocks within said openings and having complementarily stepped ends in overlapping relation to provide a long flux-leakage path between adjacent resonators.

9. A magnetron anode comprising two spaced blocks disposed side by side and having aligned openings and whose effective length is determined by the distance between said blocks, said magnetron anode having a plurality of cavity resonators separated by pairs of vanes respectively extending from the blocks within said openings and having complementarily stepped ends in overlapping relation, the adjacent vanes of each block having the steps on opposite faces thereof in avoidance of distortion of the current paths on the resonator surfaces.

10. A tunable magnetron comprising an evacuated envelope, an anode comprising spaced blocks disposed within said envelope, said magnetron having a plurality of cavity resonators separated by pairs of vanes respectively extending from the blocks with the vanes of each pair in overlapping relation, and tuning means coupled to at least one of said blocks and operable from the exterior of said envelope for varying the spacing between said blocks within limits for which said overlapping exists to adjust the effective length of said anode without production of spurious frequencies.

11. A tunable magnetron comprising an evacuated envelope, an anode comprising spaced blocks disposed within said envelope, said magnetron having a plurality of cavity resonators separated by pairs of vanes respectively extending from the blocks with the vanes of each pair in overlapping relation, and tuning means coupled to at least one of said blocks and operable from the exterior of said envelope for varying the spacing between said blocks within limits for which said overlapping exists to adjust the effective length of said anode without production of spurious frequencies, the overlapping ends of said vanes being complementarily stepped to provide for all settings of said tuning means along flux-leakage path between adjacent resonators.

12. A tunable magnetron comprising an evacuated envelope, an anode comprising spaced blocks disposed within said envelope, said magnetron having a plurality of resonant cavities separated by pairs of vanes respectively extending from the blocks with the vanes of each pair in overlap-

ping relation, and tuning means coupled to at least one of said blocks and operable from the exterior of said envelope for varying the spacing between said blocks within limits for which said

5 overlapping exists to adjust the effective length of said anode without production of spurious frequencies, the overlapping ends of said vanes being complementarily stepped to provide for all settings of said tuning means along flux-leakage path between adjacent resonators, and the adjacent vanes of each block being stepped on opposite faces in avoidance of distortion of the current paths on the resonator surfaces.

13. A tunable magnetron comprising an evacuated envelope, an anode comprising relatively movable blocks within said envelope, and means movably mounting said anode blocks within said envelope, said means being adjustable for varying the separation between said blocks and including cam structure rigidly attached to said envelope and engaging said blocks and spring means biasing said blocks into engagement with said cam structure, whereby movement of said anode blocks with respect to said envelope and attached cam structure will vary the spacing between said blocks and thus vary the effective length of said anode.

14. A tunable magnetron comprising an evacuated envelope, an anode comprising spaced relatively movable blocks disposed within said envelope, adjustable means within said envelope connecting said blocks independently of said envelope, and means disposed in part externally of said envelope and coupled to said connecting means for adjusting said connecting means to adjust the separation of said blocks and the effective length of said anode.

15. A tunable magnetron according to claim 5, wherein said one of said blocks is movably mounted in said envelope and the other of said blocks is fixed to said envelope.

16. A tunable magnetron comprising an evacuated envelope, an anode comprising spaced relatively movable anode blocks within said envelope, a plurality of spaced parallel anode elements carried by each block with the anode elements on one block overlapping the anode elements on the other block, and means within said envelope connecting said blocks independently of said envelope, said means being adjustable for varying the effective length of said anode by adjustment of the separation between said anode blocks.

17. A tunable magnetron according to claim 16, wherein said anode elements and said blocks form a plurality of cavity resonators.
